UNITED STATES PATENT OFFICE.

JOHN H. BURPEE AND DAVID E. LAIN, OF BELLINGHAM, WASHINGTON.

ENGINE PISTON.

Application filed September 12, 1922. Serial No. 587,695.

Our invention relates to improvements in engine pistons, more especially those used in internal combustion engines. We have applied for Letters Patent, Serial No. 497,680, filed Sept. 1, 1921, for a piston operating on the same general principles as the subject of this application. One of the objects of our improvements is to provide a piston which requires no packing rings but in which a zone of the main piston body is in close, gas-tight contact with the cylinder periphery during engine operation. Another object of our improvements is to provide a piston in which there is free movement between piston head and body during direct transmission of heat from said head to said body. Another object of our improvements is to provide a piston in which a zone on the inner end of the main piston body is caused to expand by operative heat from the piston head and maintain a gas-tight contact with the engine cylinder and not overbear on said cylinder to cause undue friction. Another object of our improvements is to provide a piston in which the contact with the engine cylinder is confined to a zone on the inner end of the piston. Another object of our improvements is to provide a piston which affords a direct path for heat from its head to the entire cylinder circumference through its body; and a further object of our improvements is to provide a piston adapted for quantity production by simple processes on ordinary engine lathes.

We attain these objects with the mechanism illustrated in the accompanying sheet of drawings, forming a part of this specification, in which Figure 1 is a side elevation of our piston mounted in a cylinder said cylinder being in vertical cross section on a medial plane and a part of said piston also being in vertical cross section on said plane. Fig. 2 is a top plan view of said piston and cylinder in section on the dropped line 2--2 of Fig. 1. Fig. 3 is a bottom plan view of said piston shown in Fig. 1. Fig. 4 is a side elevation of a similar piston varying in a single detail. Fig. 5 is a plan view of Fig. 4 in section on the dropped line 5--5 of Fig. 4, and Fig. 6 is a side elevation of a piston differing but slightly from the other pistons illustrated. Fig. 3 serves equally well as a bottom plan view of each of the pistons illustrated.

55 Similar characters refer to similar parts

throughout. Certain parts are broken away to show other parts hidden thereby.

More particularly: The engine cylinder is shown at A. The outer end of the main cylindrical piston body is shown at 7 and the inner end of the same at 8, and between these two ends is interior annular boss or flange 9. The inner piston end 8 is plain in Figs. 1 and 2 and thicker than outer end 7. In Figs. 4 and 5 inner end 8 is fluted longitudinally with grooves a^8 , a^8 , forming ribs b^8 , b^8 . In Fig. 6 inner end 8 is indented by annular groove d^8 above boss 9. The only differences in the three pistons illustrated reside in flutes a^8 and annular groove d^8 , for said groove can be used in either of the other forms. Oil groove c^8 is cut in the piston body exterior to boss 9. Pin holes 10 are made in bosses 11, 11 on the interior of outer end 7. Said outer end of the piston preferably ends with said pin bosses. The wrist pin is shown at 12, in Figs. 1 and 3, on which is mounted connecting rod 13. The piston head consists of cap 14 and cylindrical extension 15 thereto. Said extension has flange a^{15} which is made larger than the bore of flange 9 and forced into the same under considerable pressure to become a rigid part of the piston. Said extension is forced into said bore till the annular surface a^{14} of cap 14 is closely seated and abutting on end e^8 of the piston body. When the piston head is in place interior chamber 16 is enclosed between said head and body. In practice the diameter of the bore of boss 9 need be smaller than the diameter of the interior cylindrical surface of end 8 only to allow flange a^{15} to pass.

During operation cap 14 of the piston head expands to nearly reach the outer circumference of piston body 8 and chamber 16 must be sufficiently wide to prevent interior extension 15 from coming into contact with 8. Then when the temperature of cap 14 falls it shrinks, and thus abutting surface a^{14} moves over abutting surface e^8 . Then heat passes from cap 14 through these abutting surfaces of contact to end 8 of the piston body and causes it to expand, when said surface e^8 moves over surface a^{14} . And this relative surface movement occurs without cap 14 having any power to expand end 8 by pressure thereon. Body end 8 continues to rise in temperature and expand thereby till it comes in such close contact

- with the cooler cylinder walls A that its surplus temperature is absorbed thereby and its temperature increases no further. There is another path through which heat 5 from cap 14 reaches piston body end 8, viz., through cylindrical piston head extension 15 and the union between the same and end 8 at the surfaces of contact between boss 9 and flange a^{15} . This heat also causes end 10 8 to expand and is also absorbed by the cooler cylinder walls A. Of course, it is understood that during the movement of heat from piston walls 8 into cylinder walls A the piston is reciprocating in said cylinder. In practice it is found that said heat absorption from the piston by the cylinder is not too rapid to prevent the piston from making a gas-tight closure of the cylinder and yet sufficiently rapid to prevent the piston 15 from overbearing on the cylinder with a pressure to cause undue friction during said piston reciprocation. Enough mass of metal is placed in piston body end 8 to cause it to diminish in temperature no faster than cylinder walls A when the engine is closed down and heat is no longer created in the cylinder. The mass of metal in end 8 serves as heat storage so that, when the source of heat within cylinder A is cut off, 20 end 8 can for a short time, cool no more rapidly in its surroundings than does cylinder A in its surroundings. Then piston end 8 will continue in sealing contact with cylinder A till both have lost a considerable 25 part of their heat when end 8 will cool more rapidly than the cylinder and shrink to cause the normal clearance which pertains when both cylinder and piston are cool. This slow cooling of piston end 8 is 30 desirable in order that a quick start may be made immediately following a close-down.
- Flutes a^8 in the interior of piston end 8 serve to make the contact end of the piston 35 flexible and allow it to closely conform to oblong shapes of cylinder cross section when the cylinder has become unevenly worn. Annular groove d^8 , which may be used with the plain end 8 shown in Figs. 1 and 3 or 40 with the fluted end shown in Figs. 4 and 5, serves to localize the expansion of the inner piston end due to heat received from head 14 through slip point a^{14} , e^8 above said groove and the expansion due to heat received through extension 15 to that part of the piston below said groove.
- Having thus disclosed our invention, what we claim as new and desire to secure by Letters Patent is,—
1. In an engine piston in combination, a hollow cylindrical piston body and a piston head hermetically joined to said body between the ends thereof and abutting one of the ends of said body in a slip joint transversely of said body with an annular 60 chamber between the opposite walls of said head and body between said hermetical joint and said slip joint adapted to permit the approach of said walls near said slip joint and said slip joint adapted to transmit heat from said head to said body and permit the movement of said head on said body at said slip joint.
2. In an engine piston in combination, a hollow cylindrical piston body and a piston head hermetically joined to said body between the ends thereof and abutting one of the ends of said body in a slip joint adapted to transmit heat from said head to said body while said head is moving on said body at 65 said slip joint and having an annular chamber between the opposite walls of said head and said body and said opposite walls of said body having interior longitudinal flutes therein.
3. In an engine piston in combination, a hollow cylindrical piston body and a piston head hermetically joined to said body between the ends thereof and abutting one of the ends of said body at a transverse slip 70 joint adapted to transmit heat from said head to said body while said head is moving on said body at said slip joint and having an annular chamber between the opposite walls of said head and body between said hermetical joint and said slip joint with an annular groove in the interior of said body wall of said chamber.
4. In an engine in combination, an engine cylinder, a hollow cylindrical piston body 75 mounted for reciprocation in said cylinder, and a piston head hermetically joined longitudinally to the interior walls of said piston body between the ends thereof and also abutting the inner end of said piston body at a transverse slip joint which is adapted to transmit heat, received by said piston head from hot gases within said cylinder, from said head to said piston body while permitting the abutting surfaces of said head and said body to move on each other, whereby said piston head is expanded by 80 heat received from said hot gases without transmitting expanding pressure to said piston body adjacent to said slip joint and said piston body adjacent to said slip joint is expanded by the heat from said hot gases, received through said head and across said slip joint, to seal said cylinder by direct contact therewith as it reciprocates therein 85 under pressure of said gases.
5. In an engine in combination, an engine cylinder, a hollow cylindrical piston body 90 mounted for reciprocation in said cylinder, a piston head hermetically joined longitudinally to said piston body between the ends thereof and also abutting the inner end of said piston body at a transverse slip joint which is adapted to transmit heat, received 95 from hot gases within said cylinder by said 100
- 65

- piston head, from said piston head to said piston body end while permitting the abutting surfaces of said head and body to move on each other, whereby said piston head is 5 expanded by heat received from said hot gases without transmitting expanding pressure to the said inner end of said piston body and said piston body inner end is expanded by heat received from said hot gases through 10 said piston head and across said slip joint to seal said cylinder in direct contact there- with as it reciprocates therein under pressure of said hot gases, and power-transmis- sion connections from said piston to the 15 drive shaft of said engine.
6. In an engine in combination, an engine cylinder, a hollow cylindrical piston body mounted for reciprocation in said cylinder, a piston head hermetically joined longitudinally to said piston body between the ends thereof and also abutting the inner end of said piston body at a transverse slip joint which is adapted to transmit heat, received from hot 20 gases within said cylinder by said piston head, from said piston head to said piston body end while permitting the abutting surfaces of said head and body to move on each other, whereby said piston head is expanded by heat received from said hot gases without 25 transmitting expanding pressure to the said inner end of said piston body and said inner end is expanded by heat received from said hot gases through said piston head and seals said cylinder by direct contact there- 30 with as it reciprocates therein under pres- 35 sure of said hot gases, said inner end of said piston body massive enough to retain heat immediately subsequent to the cessation of gas heat and adapt it to contract in unison with said cylinder whereby said piston re- 40 mains in close contact with said cylinder immediately following a close-down of said engine, and power-transmission connections from said piston to the drive shaft of said engine. 45
7. In an engine piston in combination, a hollow cylindrical piston body and a piston head hermetically joined to said body between the ends thereof and abutting one of the ends of said body in a slip joint adapted 50 to transmit heat from said head to said body while said head is moving on said body at said slip joint and having an annular cham- 55 ber between the opposite walls of said body and said head and said opposite walls of said body having embossures on their in- terior projecting into said chamber.
8. In an engine piston in combination, a hollow cylindrical piston body and a piston head adapted to close said body in a longi- 60 tudinal joint between the ends thereof and further adapted to abut one end of said body in transverse contact also whereby is en- closed an annular chamber between said longitudinal closure and said abutting ends. 65
